UNITED STATES PATENT OFFICE

CHARLES J. WEBER, OF CHICAGO, ILLINOIS, ASSIGNOR, BY MESNE ASSIGNMENTS, TO THE FOOTE COMPANY, INC., OF NUNDA, NEW YORK, A CORPORATION OF DELAWARE

CONCRETE MIXER

Application filed June 16, 1923. Serial No. 285,991.

My invention relates, generally, to concrete mixers and pavers and more particularly to improved means for charging the mixer with aggregate and water and to improved means for controlling the operation of the discharging means.

It is an object of my invention to provide improved means for raising and lowering the charging skip of concrete mixers and pavers in which the use of wire rope cables has been eliminated.

A further object is to provide improved means for operating the charging skip which permits of a decrease in the over-all height of the mixer.

A further object is to provide an improved means for raising and lowering the charging skip of a concrete mixer which is automatically held in raised position and requires the application of power to lower it.

A further object is to provide improved automatic means for controlling admission of water.

A further object is to provide improved means for controlling the operation of the discharge chute.

Other objects will appear from the following description, reference being had to the accompanying drawings, in which—

Fig. 1 is a side elevation of a concrete mixer which shows, generally, the improvements of my invention;

Fig. 2 is a perspective view of the charging end of the concrete mixer showing the charging skip in elevated position;

Fig. 3 is a side elevation of the charging end of the mixer showing particularly a portion of the means utilized to control the operation of the discharge chute;

Fig. 4 is an elevation of the side opposite Fig. 3 showing particularly the means for controlling the admission of water;

Fig. 5 is an elevation of a portion of the means used to control the operation of the discharge chute;

Fig. 6 is a perspective view of the clutch and gearing mechanism utilized to operate the charging skip;

Fig. 7 is a somewhat diagrammatic plan

view of the gearing utilized in raising and lowering the charging skip;

Fig. 8 is a detail view of the reversing clutch mechanism for raising and lowering the charging skip; and

Fig. 9 is a fragmentary sectional view taken on the line 9—9 of Fig. 7 and showing particularly the charging skip elevating clutch knock-out mechanism.

In the past it has been common practice to utilize cables, usually one attached to each side of the charging skip, to raise and lower the same. This method of operating the charging skip has serious disadvantages in that the over-all height of the mixer is greatly increased due to the necessity of having elevated cable sheaves or winding drums placed some distance above the top of the mixer.

The superstructure necessary to hold these sheaves or winding drums must frequently be dismantled to permit the mixer to be shipped by railroad and to permit it to pass beneath bridges and other obstructions over the highway. The dismantling and reassembling of the superstructure not only consumes a great amount of time, but occasionally, due to the relatively unskilled labor commonly employed for this type of work, the superstructure is not assembled properly.

Furthermore, the wire rope or cables employed in raising the charging skip rapidly wear out in use, requiring frequent replacement and consequent loss during the time which the machine is necessarily idle while making such replacements. In some instances, the cables break, permitting the charging skip to fall. The falling of the charging skip has in the past resulted in a number of serious and several fatal injuries to the workmen. In the construction which I have invented I have entirely eliminated the use of cables for hoisting the charging skip and have provided skip elevating means which automatically prevent the charging skip from falling. The improvements of my invention are particularly adapted for use in the Foote concrete pavers but with suitable slight changes may readily be incorporated in any concrete mixer or paver.

Referring to Figs. 1 and 6, the paver comprises a base frame 12 mounted upon suitable traction means 14. The usual steel framework is carried by the base frame 12. The mixer includes the usual rotary mixing drum 16 mounted for rotation upon trunnion rollers 18, the drum being rotated by one or more driving pinions 22 which are in mesh with ring gears 20 secured to the drum. A charging spout 24 is mounted at the charging end of the drum and is adapted to guide the aggregate into the drum. A charging skip 26 is pivoted at 28 in brackets suitably secured to the frame of the machine.

15 *Means for raising and lowering the charging skip*

The mixer is driven by an engine or motor 30 which, as represented in Fig. 7, is connected through a suitable gear speed reduction mechanism to a drive shaft 32. The shaft 32 (Figs. 6 and 7) has a drive gear 34 and a sprocket 36 non-rotatably secured thereto. The drive gear 34 meshes with a driven gear 38 which is normally freely rotatable upon a countershaft 40 and is formed integral with a clutch housing 42. The sprocket 36 is connected by means of a chain 44 with a sprocket 46 which is secured to or formed integral with a plate 48, the sprocket and plate being freely rotatable upon the shaft 40.

The plate 48, together with a similar plate 50 and a friction disc 52, form a friction clutch, the plate 50 having a hub 51 with a suitable annular groove 54 adapted to receive roller pins 56 carried in the bifurcated clutch actuating arm 58, the latter being rigidly secured to a shaft 60.

The end of the hub 51 is tapered so as to be adapted to engage clutch fingers 62 and thereby operate the friction clutch contained within the housing 42. The hub 51 is keyed to the shaft 40 and thus is adapted to form a driving connection between either the clutch housing 42 or the plate 48 and the shaft, depending upon whether it is thrown to the right or the left.

The shaft or rod 60 has an arm 64 rigidly secured thereto, a link 66 being pivotally connected at the end of the arm. The upper end of the link 66 is connected to a suitable operating handle whereby it may be raised or lowered. By raising the link 66, the shaft 60 will be oscillated clockwise (Fig. 9) so as to throw in the clutch within the housing 42, whereas when the link 66 is operated downwardly, it will rotate the shaft 60 counterclockwise and throw in the friction clutch 48-52-50.

The end of the shaft 60 carries an arm 68, at the end of which a link 70 is pivotally connected. As will hereinafter appear, the link 70 is moved to the left (Figs. 7 and 9) as the charging skip reaches its uppermost position,

thereby to disengage the clutch within the housing 42.

The countershaft 40 has a sprocket 72 secured at its right-hand end, the sprocket being connected by a chain 74 with a similar sprocket 76. The sprocket 76 is keyed to one end of a shaft 78, the other end of which carries a spur-gear 80. The spur-gear 80 meshes with a pinion 82 keyed on a shaft 84. The shaft 84 carries a worm 86 which is in engagement with a worm wheel 88, the latter being keyed to a shaft 90. A pair of pinions 92 and 94 is keyed to the ends of the shaft 90. The worm and worm wheel are preferably mounted within a casing 96 which is adapted to be 80 filled with a suitable lubricant.

A pair of elevating arms 98, 99 is keyed at the ends of a shaft 100 which is rotatably mounted in suitable bearing brackets 102. Spur-gear teeth 104, cut at the inner ends of the arms 98, 99, form segmental gears which are in mesh with the pinions 92 and 94, respectively. The outer ends of the arms 98, 99 carry a bail rod 106. Links 108, pivotally connected to brackets 110 bolted or riveted to the charging skip, have elongated slots 112 formed at their lower ends, these slots receiving the bail rod or shaft 106. Suitable collars 114 on the shaft 106 prevent lateral movement of the links.

The arm 99 has a pin 116 extending sidewardly therefrom which is adapted, as the charging skip approaches its uppermost position, to contact with the upper end of a lever 118 which is pivoted at 119 and swing it counterclockwise (Fig. 3), thereby moving the link 70 to the right (Fig. 3) or to the left (Figs. 7 and 9). As previously described, such movement of the link 70 will throw out the skip elevating clutch.

105 *Discharge chute controlling mechanism*

It is desirable, in machines of this kind, to provide means for insuring that the discharge chute is in non-discharging position as the charging skip reaches its elevated or charging position, and if the discharge chute happens to be in discharging position, automatically to move it to non-discharging position as the charging skip is being elevated. I have provided a simple mechanism for accomplishing this purpose.

A cam plate 120 is secured to the pinion 92 and is adapted to engage a roller pin 122 carried at the end of one arm of a bell crank lever 124, the latter being pivotally mounted in a bracket 126 secured to the frame of the machine. During the initial elevating movement of the charging skip, the cam plate 120 engages the roller pin 122 and swings the bell crank 124 counterclockwise (Fig. 3), thereby moving upwardly a rod 128 which is pivotally connected to the other arm of the bell crank lever 124. The upper end of the rod 128 is 130

pivotedly connected to the end of an arm 130 which is keyed to a shaft 132.

The end of the shaft 132 has a bevel gear 134 keyed thereto, the latter meshing with a similar bevel gear 136 secured to the end of a shaft 138. It will thus be seen that through the above described connections, the shaft 138 will be rotated clockwise (Fig. 5), when the charging skip is being elevated and, as will hereinafter appear, the discharge chute is in discharging position.

An arm 140 (Fig. 5) is attached to the end of the shaft 138 opposite the bevel gear 136, the end of this arm being pivotally connected to a link 142 which at its lower end is pivotally connected to one end of a lever 144 which is suitably pivoted to the stationary frame at 146.

A spring 147, anchored to the frame at one end and to the end of the arm 140 at the other, normally tends to hold the parts in the position shown in Fig. 5.

The end of the lever 144 lies between stop pins 148 and 150 which are secured upon a link 152. The link 152 connects the end of an arm 154 with an arm 156. The arm 154 is keyed to a shaft 158 to which a hand operating lever 160 is also keyed. The arm 156 is keyed to a shaft 162 which also carries an arm 164, at the end of which a roller 166 is rotatably mounted. The roller 166 is adapted to drop into one of two notches 168 formed in a drum 170, the drum 170 being a part of a planetary gear train which is more fully disclosed and described in the patent to Foote, No. 1,561,144, granted November 10, 1925. Suffice it here to say that rotation of the drum 170 causes rotation of an eccentric about which an eccentric strap 172 is attached. The strap 172 is connected to one arm 174 of a bell crank lever 176 by means of a link 178. The bell crank lever 176 is pivotally mounted on the frame at 180 and the other arm 182 of the bell crank 45 is pivotally connected to an adjustable operating rod 184. The other end of the latter is pivotally joined to a rotatably mounted discharge chute frame 186 which carries the discharge chute 188.

A cable 189 of flexible wire rope, connects the end of arm 174 of the bell crank 176 with the end of arm 140 for a purpose as will hereinafter more fully appear.

As will more fully appear from the aforesaid patent, clockwise movement (Fig. 5) of the arm 156 will raise the roller 166 out of its notch and at the same time tighten the brake band 190 which will serve to connect the power drive to rotate the drum 170 and hence lower the link 178 and thereby move the discharge chute to discharging position. As soon as the drum 170 has rotated through an angle of 180 degrees, the roller 166 will drop into the opposite notch 168 and there-

by release tension on the brake band 190 and disengage the power drive connection.

Water control mechanism

As more fully disclosed in the patent to Foote, No. 1,590,359, granted June 29, 1926, the mixer is provided with a water tank 192 and a three-way valve 194. This valve is adapted to be opened by raising a link 196 which at its lower end is connected to an arm 198. The arm 198 has a sidewardly projecting ear 200 and the long arm 202 of a bell crank lever 204 has a similar sidewardly extending lug 206 formed integrally therewith. A bolt 208 passes between these two lugs and a spring 210 is compressed between the lugs, thus forming a cushioning buffer between the arms 198 and 202.

The arm 202 has one end of a spring 212 secured thereto, the other end of the spring being suitably anchored to the frame of the machine. The bell crank lever 204 has a short arm 214 having a pin and roller 216 which is adapted to engage the flanged surface of a cam plate 218 which is rigidly secured to the elevating arm 98.

As the arm 98, and hence the charging skip, approaches its uppermost position, the surface of the cam 218 will engage the roller and pin 216 and swing the bell crank lever 204 clockwise about its pivot 220, thereby through the buffer connection raising the link 196 and opening the three-way water valve to permit flow of water from the tank 192 into the drum.

Operation

Assuming the charging skip to be in its lowermost position and a charge having been loaded therein, the operator will raise the link 66 with a suitable hand lever and thereby pivot the shaft 60 clockwise (Figs. 6 and 9), thereby throwing in the clutch within the housing 42 and connecting the driven gear 38 with the sprocket 72.

Power will be transmitted from the sprocket 72 through the chain 74, sprocket 76, shaft 78, gears 80, 82, shaft 84, worm gear 86, worm wheel 88, shaft 90 and pinions 92, to the arms 98, 99. The arms 98, 99 will thus be moved counterclockwise (Figs. 1 and 4) and after taking up the lost motion due to the elongated slots 112 in the links 108, will, through the links 108, raise the charging skip. The elongated slots 112 are provided so that the skip may be moved downwardly to different degrees, depending upon the level of the ground adjacent the mixer.

As the charging skip is being elevated, it is desirable, of course, to move the discharge chute to non-discharging position if the chute is not already in that position. This is accomplished through the following train of linkage and gearing:

The cam 120 on the pinion 92 will, if the

discharge chute is in discharging position, engage the pin and roller 122 on the bell crank 124 and move the latter counterclockwise, raising the link 128, oscillating the shaft 130 clockwise (Fig. 3) and thereby oscillating the shaft 138 clockwise (Fig. 5). Clockwise rotation of this shaft with its arm 140 will depress link 142 and thereby pivot lever 144 about its pivot axis 146, raising the right-hand end of this lever until it engages the pin 150 and thereby raising the link 152 which in turn will operate the power discharge mechanism to move the discharge chute to the non-discharging position shown in Fig. 5. If, however, the discharge chute is already in non-discharging position, the spring 147 will hold the arm 140 and hence the shaft 138 in the position shown in Fig. 5. When these parts are in this position, the bell crank 124 will have been moved counterclockwise to its furthest position so that its pin roller 122 will not lie in the path of cam plate 120.

When, however, the discharge chute is in discharging position, as shown in dotted lines in Fig. 5, the cable 189 will have been pulled downwardly, thereby swinging the arm 140 slightly clockwise and through the shaft 138, bevel gears 136, 134, shaft 132, arm 130, and rod 128, moving the bell crank clockwise so that its pin roller 122 lies in the path of the cam 120. Thus the cable 189 serves as a means for determining whether or not the power-operated discharge chute mechanism shall be operated.

The power-operated discharge chute mechanism operates rapidly so that the chute will be in non-discharging position by the time the charging skip is sufficiently elevated to permit the aggregate to flow into the mixing drum. As the charging skip approaches the charging position, the cam 218 on the elevating arm 98 engages with the pin roller 216 and through the bell crank 204 and its extension arm 198 raises the link 196 and thereby opens the three-way water valve 194 to permit the water to flow into the mixing drum with the aggregate.

When the charging skip reaches its most elevated position, the pin 116 on the arm 99 engages lever 118 and thereby moves the link 70 to the right, as shown in Fig. 3, or to the left, as shown in Figs. 7 and 9, thereby oscillating the shaft 60 counterclockwise and disengaging the clutch in the housing 42. Disengagement of the clutch 42 results in the disconnection of the power to the charging skip elevating mechanism.

The pitch of the worm 86 and worm wheel 88 is such that it is non-reversible; that is, the weight of the skip and its contents will not rotate the worm shaft 84 and the skip is thus firmly held in its raised position. It is thus necessary to apply power to the worm in a reverse direction in order to lower the

skip. This is accomplished by oscillating the shaft 60 counterclockwise (Figs. 6 and 9) by manually lowering the link 66, thereby throwing the friction clutch 48-52-50 into engagement. The drive will then be from shaft 32 through sprocket 36, chain 44, sprocket 46, clutch 48-52-50, shaft 40, sprocket 72, etc., to the charging skip.

The clutch 48-52-50 is a reversing clutch and thus drives the worm 86 in a direction reverse to that when driven through the clutch 42 and will thus lower the charging skip. As the charging skip begins to be lowered, the pin roller 216 is freed from engagement with the cam 218 and the bell crank 204 is permitted to swing counterclockwise under the influence of the spring 212, thereby to shut off the three-way water valve.

During the lowering operation, the pin roller 122 will, of course, be held out of the path of cam plate 120 by the spring 147, so that the discharge chute will not be operated.

The invention is capable of wide variation within equivalent limits and I contemplate such variation as may be desirable or useful in the particular adaptation of the invention shown, or in its adaptation to other machines. I do not restrict myself in any unessential particulars, but what I claim and desire to secure by Letters Patent is:

1. In a machine of the class described, the combination of a mixing drum, a pivoted charging skip, means for positively raising and lowering said skip, said means including a driving pinion; a power operated discharge chute, a cam on said pinion, and means actuated by said cam to control the operation of said discharge chute.

2. In a machine of the class described, the combination of a mixing drum, a charging skip, means for positively raising and lowering said skip, said means including a driving pinion; a power operated discharge chute, a cam on said pinion, means actuated by said cam to cause the operation of said discharge chute from discharging to non-discharging position, and means for rendering said last-named means inoperative when said discharge chute is in non-discharging position.

3. In a machine of the class described, the combination of a mixing drum, a pivoted charging skip, pivotally-mounted arms for positively raising and lowering said charging skip, a cam on one of said arms, a valve for controlling the admission of water to said drum, linkage for operating said valve, and yieldable means actuated by said cam for operating said linkage.

4. In a machine of the class described, the combination of a mixing drum, a pivoted charging skip, pivotally-mounted arms for positively raising and lowering said charg-

ing skip, a cam on one of said arms, a valve for controlling the admission of water to said drum, yieldable means actuated by said cam for opening said valve, and resilient means for closing said valve.

5 5. In a concrete mixer, the combination of a mixing drum, a charging skip pivoted relative to said drum, a pivotally-mounted skip raising arm having its end attached to said skip by a lost motion link connection, an irreversible worm and worm wheel for swinging said arm, a power drive shaft, a clutch for operatively connecting said power drive shaft with said worm, and means for disengaging said clutch after said arm reaches a predetermined position, said means including a lever operated by said arm.

10 6. In a machine of the class described, a discharge chute, mechanism for moving said discharge chute from charging to non-discharging position, power means for actuating said mechanism, a manually operable lever for controlling said means, a charging skip, and means, operated as an incident to the movement of said charging skip to a predetermined position, to control the operation of said power means, comprising a lever adapted to be moved by said skip, a spring for holding said lever in normal inoperative position, and a lost motion connection between said lever and said mechanism whereby said lever will be moved into operative position when said discharge chute is in discharging position.

15 7. In a machine of the class described, a discharge chute, mechanism for operating said discharge chute, power means for actuating said mechanism, a manually operable lever for controlling said means, a charging skip, and means, operated as an incident to the movement of said charging skip, to control the operation of said power means, comprising a cam operated when said skip is operated, a follower, a spring for holding said follower out of the path of the cam, and a flexible connection between said follower and said mechanism whereby said follower will be moved into the path of said cam when said discharge chute is in discharging position.

20 8. In a machine of the class described, the combination of a mixing drum, a pivoted charging skip, means for positively raising and lowering said skip, said means including a driving shaft and pinion; a power operated discharge chute, and means movable with said driving shaft to control the operation of said discharge chute.

25 9. In a machine of the class described, the combination of a mixing drum, a pivoted charging skip, pivotally mounted arms for positively raising and lowering said charging skip, a valve for controlling the admission of water to said drum, a linkage for operating said valve, and yieldable means for operating

said linkage, said yieldable means being actuated by the movement of one of said arms.

In witness whereof I hereunto subscribe my name this 8th day of June, 1928.

CHARLES J. WEBER.
